ROTARY VALVE

Rudolph Wehr, Baptists, N. J.

Application October 12, 1940, Serial No. 360,863

8 Claims. (Cl. 123—190)

The present invention relates to rotary valves, and more particularly to a type adapted for use in internal combustion engines for controlling the admission and discharge of gases to and from the combustion cylinder.

One object of the present invention is to provide a rotary valve, having its relatively slidable parts maintained in proper slidable working gas-tight contact with a minimum amount of wear and gas leakage, even under conditions of widely varying temperature and pressure.

Another object is to provide a rotary valve, having relatively slidable parts adapted to become self-worn into effective gas-tight seating contact after a comparatively short period of use.

Another object is to provide a rotary valve having new and improved means for lubricating its various operating parts.

Various other objects of the invention will be apparent from the following particular description, and from an inspection of the accompanying drawing, in which—

Fig. 1 is a sectional view of a portion of an internal combustion engine, provided with a valve mechanism embodying one form of the present invention.

Fig. 2 is a transverse section of one of the rotary valves taken on line 2—2 of Fig. 1.

Fig. 3 is a fragmentary section on an exaggerated scale of a sharp serration, formed on the surface of one of the relatively slidable parts of the valve mechanism, and shown before the sharp edges of its ridges have been worn into gas-tight seating contour.

Fig. 4 is a fragmentary section of the serration of Fig. 3 after the sharp edges of the ridges have been worn into gas-tight seating contour, and

Figs. 5 and 6 are transverse sections of different forms of valve mechanisms respectively, embodying the present invention.

The present application is a continuation in part of my co-pending application Serial No. 328,503, filed April 8, 1940.

Referring specifically to Figs. 1 to 4 of the drawing, the invention is shown applied to an engine having a series of combustion cylinders 10, closed at one end by a cylinder head 11, provided with a bore 13 for housing a series of rotary valve members 12 in axial alignment. The valve housing 11 is provided at each section thereof above its corresponding cylinder 10 with an intake port 14, an exhaust port 15 and a cylinder port 16, disposed between said intake and exhaust ports. Each rotor 12 is provided with two symmetrically arranged recesses or passageways 17, 55

adapted to connect the cylinder port 16 with the intake port 14 and exhaust port 15 in proper sequence upon rotation of said rotor.

In the type of rotary valve in which the housing 5 serves as a bearing for the rotor, the pressure exerted by the gases in the cylinder, especially during compression and explosion, tends to lift the rotor away from its seat at the cylinder port 16 and against the section of the housing opposite said seat. This may result in leakage past the valve, and the binding or seizing of the rotor against rotation. To avoid this, the valve sections 12 are supported by intermediate anti-friction bearings 18, each comprising an outer race 19, affixed at its outer periphery in the bore 13 of the housing 11, an inner race 20, and a series of bearing balls 21 between said races. Each valve section 12 is provided at each end with a boss 22 abutting the end of the inner race 20, 10 and a shaft or trunnion 23 of reduced diameter extending axially from said boss into the bore of said inner race. The opposed shafts 23 of adjoining rotors 12 are keyed or otherwise affixed together or to the inner races 20, so that 15 all the valve sections are co-axially connected for rotation in unison. The rotation of these rotors may be effected in any manner well-known in the art. Thus the weight of each valve section is supported solely by the bearings at the ends 20 thereof and neither high pressure nor partial vacuum in the engine cylinder effects any change 25 in the spacing between the periphery of the valve sections and the juxtaposed casing wall.

In order to maintain the valve sections 12 and 30 the housing 11 in proper gas-tight seating contact under varying conditions of heat and pressure, the seating section of one of said members is serrated to form a series of V-shaped ridges 25 of small cross-section, extending transversely 35 to the direction of relative movement of said members. In the construction shown in Figs. 1 and 2, the main central section of the valve section 12 is provided with said ridges 25 along its two opposed circular peripheral surface portions 26, which are concentric with the shafts 23, and 40 which are adapted to rotate successively into seating contact with the lower smooth circular seat 27 of the housing 11 extending between the two ports 14 and 15.

Before the valve has been operated, the ridges 50 25 may be sharp at their crown edges or high points 28 as shown in Fig. 3, and contact the opposed smooth surface 27 when cold, and are small enough to be worn down at these points 55 as shown in Fig. 4 into conforming gas-tight

seating relationship with said surface 27 after a comparatively short period of use, with the valve expanded by heat. As an example, the distance between adjacent ridges 25 may be not to exceed $\frac{3}{8}$ of an inch, and the parts so dimensioned and so designed that these ridges will be worn down at their high points to a width of possibly $\frac{1}{2}$ of an inch, when the expansion is at its maximum and the ridges are in gas-tight engagement with the seating surface 27 of the housing. Thus it will be seen that the areas of the outer faces of the ridges in the serrated area constitute only a very small portion of the original area before the serrations are formed, and that the width of the outer face of each ridge, even after wearing away, is only about one third of the distance from ridge center to ridge center. As the outer faces of the ridges do not support any load from the weight of the valve or of the pressure applied to the valve during operation of the engine, it is not important that the outer faces of the ridges have any appreciable width. The ridges serve merely as partitions between adjacent grooves. It is important that there be a large number of narrow grooves in which minute eddies of gas may occur and in which there may be a large number of successive drops in pressure between the cylinder port 16 and the exhaust port 15. Thus, even though the faces of the ridges may only lightly contact with, or be even slightly spaced from, the casing wall, there will be practically no leakage of pressure from the cylinder port to the exhaust port and across the valve seat. It is also important that the gas volume of the grooves be very small so that there will be the minimum of high pressure gas carried by each groove in traveling from the cylinder port to the exhaust port. This serrate formation between the rotors 12 and the housing 11 reduces to a minimum the contact area between these members, thereby materially reducing wear between said members. At the same time, it forms an effective gas-tight seating contact between the relatively sliding parts without the necessity of the usual expensive and time consuming grinding or machining operations. The parts grind themselves to the proper fit and with minimum removal of metal.

The valve may expand and contract somewhat; with changes in temperature, for instance, it may be slightly smaller when cold than when heated up after running for some time. When starting the engine, the clearance between the valve and its seat around the cylinder ports may be such as to permit slight leakage, but as any such leakage will flow at right angles to the serrations, its velocity will be so reduced that the leakage will be negligible. When the valve heats up and expands, the valve will directly seat around the cylinder port, but the metal surfaces directly in sliding contact and the friction and wear will be greatly reduced due to the serrations. The sharp edges of the serrations will act to scrape any accumulation of carbon from the opposite wall and such carbon will collect, to some extent, in the grooves. In case any metal particles be scraped off or dislodged from, or worn off the directly contacting metal surfaces, particularly when the parts are first assembled and run, such particles will collect in the grooves and will not act to score the opposing surface.

If the bearings 18 should become worn, the rotors 12 are apt to be lifted away from their seat and towards the section of the housing diametrically opposite said seat, by the pressure of the gases in the cylinder. Under these con-

ditions, wear of the slide parts is apt to increase, and the rotor is apt to bind or seize in its housing. In order to avoid this condition, the cylindrical valve chamber 28 of the bore 13 opposite to the port 16 may be of slightly larger diameter than the valve member 12, and eccentric with respect to said valve member, which is concentric with the smaller part 31 of the bore 13 adjacent to the port 16, and which tangentially seats on the lower surface of said chamber. There is thus provided a clearance 32 between the valve and the upper part of said valve chamber. This clearance 32, although shown in Figs. 1 and 2 on an exaggerated scale, actually has a maximum width of only a few thousandths of an inch. The three ports 14, 15 and 16 open into the valve chamber 28 within the lower semi-circular part thereof, and since the difference between the diameter of the rotor and that of said chamber is very small, there will be little or no leakage from one port to another. Such expansion as may occur in the valve will not cause it to grind against the upper surface of the valve chamber or cause it to bind if the upper surface of the valve chamber be slightly eccentric, as above described. The roller bearings between the successive valve sections prevent the valve as a whole from flexing under high pressure from the engine cylinder and there will be substantially no possible flexing of each valve section between the adjacent roller bearings, due to the large diameter and short length of said sections.

The outer race rings of the roller bearing are preferably of the same diameter or of but slightly larger diameter than the valve section and thus the valve member and its bearings may be assembled as a unit and readily slid or otherwise moved into position.

If the bearings wear sufficiently to permit slight lifting of the valve sections 12 from their seats, this will not be sufficient to effect contact between the rotor and the upper part of the enlarged valve chamber 28, so that wear of these relatively slideable parts is reduced to a minimum, and the possibility of jamming or binding of the valve rotor is eliminated.

To prevent gas leakage endwise of the valve, each of the rotors or valve sections is provided near each end with a peripheral groove 35 to receive a split metal packing ring 36 of the piston ring type, expandable into sealing engagement with the peripheral wall of the housing 11.

For lubricating the various parts of the valve mechanism, the ends of the rotors 12 are spaced from the corresponding ends of the bearings to form lubricant chambers 41 and 42 on opposite sides of each bearing, and the lower section of the housing 11 is recessed at spaced intervals to provide a sump 43 interconnecting said chambers 41 and 42. Lubricating oil is introduced desirably under considerable pressure into one of each adjoining pair 41, 42 through inlets 44 at the top, and is desirably exhausted from each sump 43 through a discharge pipe 45 connected to a vacuum pump (not shown), which may return the oil to the crank-case of the engine. This pump should operate at a higher vacuum than that produced in the engine cylinders to prevent the periodic vacuum in said cylinders from pumping the lubricant to said cylinders. The oil delivered into the chambers 41 and 42 serves to lubricate the bearings and the shafts 23.

In order to feed lubricating oil to the seating sections of the rotors 12 and the housing 11, and

to the packing rings 38, each rotor is provided beyond its serrated portions and on opposite sides of each ring with a pair of circular sections 47 and 48, formed on the periphery with fine shallow screw threads of comparatively small pitch. The threads of the rotor section 47 have a lead or direction, which when the rotors 12 are rotated, effects screw feeding of the oil from the chambers 41 and 42 along said thread to the rings 38, to lubricate said ring. The lead of the threads of the rotor sections 48 is such as to pick up what little oil leaks past the rings 38, and screw feed it to the valve chambers 28 to lubricate the slide parts therein. The lead of the threads on the rotor sections 47 and 48 to produce the oil feeding effect above noted depends on the direction of rotation of the rotors. If, for instance, the rotors 12 are driven in counter-clockwise direction as viewed in Fig. 2, the right hand pair of rotor sections 47 and 48 of each rotor will have left hand threads, while the left hand pair of rotor sections 47 and 48 of said rotor will have right hand threads.

In Fig. 5 is shown a form of rotary valve, in which the bore 13a of housing 11a is of uniform diameter throughout its valve length, and the rotors 12 fit concentrically in said bore. Although this embodiment of the invention does not have the eccentric bore enlargements 28 of Figs. 1 and 2, it has the advantage of being cheaper to manufacture because of the uniformity in the size of the bore 13a. In all other respects, the construction of Fig. 5 may be similar to that of Figs. 1 and 2.

In the construction of the rotor valve shown in Fig. 6, the seating sections 28b of the rotors 12b are of smooth cylindrical form, while the self-seating serrations 28b similar to those shown in Fig. 3 are formed in the inner periphery of the valve chamber sections of the housing bore 13b. These serrations extend along the bottom and top of the valve chamber, and the high sharp points thereof are adapted to be self-worn by the scraping action of the rotors 12b into the shape shown in Fig. 4 for gas-tight conforming contact with said rotors. As in the construction of Fig. 5, the rotors 12b are concentrically mounted in their respective valve chambers.

As many changes could be made in the above construction and many apparently widely different embodiments of the invention would be made without departing from the scope of the claims, it is intended that all matter contained in the above description or shown in the accompanying drawing shall be interpreted as illustrative and not in a limiting sense.

The present invention, insofar as it relates to the lubrication of the valve, is not herein claimed but is claimed in my copending application Serial No. 474,941, filed February 6, 1943.

Having thus described my invention, what I claim as new and desire to secure by Letters Patent is:

1. A rotary valve mechanism for multi-cylinder, internal combustion engines including a valve casing member having a plurality of axially spaced sets of peripherally spaced ports, one set for each cylinder of the engine and each set including an inlet port, an exhaust port and a cylinder port, a rotary valve member in said chamber and including a plurality of sections, one section for each set of ports and each section having a passage for interconnecting the corresponding cylinder port with the inlet and

outlet ports alternately, a plurality of bearings in said casing for supporting and centering said valve member independently of any contact of the valve sections with the casing, each bearing being disposed between two adjacent valve sections for supporting the latter, whereby flexing of said valve member by pressure exerted thereon through said cylinder ports is prevented and the sections between said bearings maintained in fixed spacing in respect to the valve casing except for the changes due to expansion and contraction of the parts, the surface of one of said members having small closely spaced longitudinal serrations for retarding lateral flow of gas from said cylinder port between said members, and the outer parts of said serration being adapted to be worn into conforming substantially gas-tight seating contact with the opposed surface of the other member at opposite sides of said cylinder port and to provide faces of substantially less width than that of the grooves between said serrations.

2. A rotary valve mechanism for multi-cylinder, internal combustion engines including a valve casing member having a cylindrical chamber of substantially uniform diameter throughout its length and provided with a plurality of axially spaced sets of peripherally spaced ports, one set for each cylinder of the engine and each set including an inlet port, an exhaust port and a cylinder port, a rotary valve member in said chamber and including a plurality of sections, one section for each set of ports and each section having a passage for interconnecting the corresponding cylinder port with the inlet and outlet ports alternately, a plurality of bearings in said casing for supporting and centering said valve member, each bearing being disposed between two adjacent valve sections for supporting both and having an outer race ring, the external diameter of which is but slightly greater than that of the adjacent valve sections whereby the valve sections and roller bearings form a unit of substantially the same diameter throughout its effective length, and whereby flexing of said valve member by pressure exerted thereon through said cylinder ports is prevented, the surface of one of said members having longitudinal serrations, the outer faces of which are in seating contact with the casing at opposite sides of said cylinder port and of substantially less area than that of the grooves between said serrations.

3. A rotary valve mechanism for multi-cylinder, internal combustion engines including a valve casing member having a plurality of axially spaced sets of peripherally spaced ports, one set for each cylinder of the engine and each set including an inlet port, an exhaust port and a cylinder port, a rotary valve member in said chamber and including a plurality of sections, one section for each set of ports and each section having a passage for interconnecting the corresponding cylinder port with the inlet and outlet ports alternately, a plurality of bearings in said casing for supporting and centering said valve member, each bearing being disposed between two adjacent valve sections for supporting both, whereby flexing of said valve member by pressure exerted thereon through said cylinder port is prevented, said valve casing having portions opposite to said cylinder ports disposed eccentrically in respect to the axis of said valve member to prevent seating of the valve in said

portions, and each of said valve sections having the surface thereon between the ends of said passage provided with longitudinal closely spaced grooves whereby the area of seating surface of the valve member and the casing member adjacent to the cylinder port is reduced by over one half and the flow of gas from said port over said surface is retarded.

4. A rotary valve mechanism for multi-cylinder, internal combustion engines including a valve casing member having a plurality of axially spaced sets of peripherally spaced ports, one set for each cylinder of the engine and each set including an inlet port, an exhaust port and a cylinder port, a rotary valve member in said chamber and including a plurality of sections, one section for each set of ports and each section having a passage for interconnecting the corresponding cylinder port with the inlet and outlet ports alternately, a plurality of bearings in said casing for supporting and centering said valve member, each bearing being disposed between two adjacent valve sections for supporting both, whereby flexing of said valve member by pressure exerted thereon through said cylinder port is prevented, said valve casing having portions opposite to said cylinder ports disposed eccentrically in respect to the axis of said valve member to prevent seating of the valve in said portions, and the surface of one of said members having closely spaced longitudinal serrations with intervening grooves for retarding lateral flow of gas from said cylinder port between said members, and the outer faces of said serration being in substantially gas-tight seating contact with the opposed surface of the other member at opposite sides of said cylinder port, and the width of each face being only about one half of the width of the adjacent groove.

5. A rotary valve mechanism for multi-cylinder, internal combustion engines including a valve casing having a plurality of axially spaced sets of peripherally spaced ports, one set for each cylinder of the engine and each set including an inlet port, an exhaust port and a cylinder port, a rotary valve in said chamber and including a plurality of sections, one section for each set of ports and each section having a passage for interconnecting the corresponding cylinder port with the inlet and outlet ports alternately, a plurality of bearings in said casing for supporting and centering said valve member, each bearing being disposed between two adjacent valve sections for supporting both, whereby flexing of said valve member, by pressure exerted thereon through said cylinder port is prevented, and each of said valve sections having the surface thereon between the ends of said passage provided with narrow, sharp edged longitudinal serrations whereby the area of seating surface of the valve member on the casing member adjacent to the cylinder port is reduced by substantially less than one half, and whereby the escape of gas from said port over said surface is retarded when said port is closed by said valve.

6. A rotary valve mechanism for multi-cylinder, internal combustion engines including a valve casing member having a plurality of axially spaced sets of peripherally spaced ports, one set for each cylinder of the engine and each set including an inlet port, an exhaust port and a cylinder port, a rotary valve member in said chamber and including a plurality of sections,

one section for each set of ports and each section having a passage for interconnecting the corresponding cylinder port and the inlet and outlet ports alternately, a plurality of bearings in said casing for supporting and centering said valve member, each bearing being disposed between two adjacent valve sections for supporting both, whereby flexing of said valve member, by variations in the pressure exerted thereon through said cylinder port is prevented, said valve casing having portions opposite to said cylinder ports spaced from said valve to prevent seating of the valve in said portions, and each of said valve sections having the surface thereon between the ends of said passage provided with narrow closely spaced longitudinal serrations whereby the area of seating surface of the valve member and the casing member adjacent to the cylinder port is reduced by over one half and the flow of gas from said port over said surface is retarded when said port is closed by said valve.

7. A rotary valve mechanism for multi-cylinder, internal combustion engines including a valve casing member having a plurality of axially spaced sets of peripherally spaced ports, a rotary valve member in said chamber and including a plurality of sections, one section for each set of ports and each section having a passage for interconnecting the ports of said set, a plurality of roller bearings in said casing for supporting and centering said valve member, each bearing being disposed between two adjacent valve sections for supporting both, whereby flexing of said valve member, by variation in the pressure exerted thereon through said cylinder port is prevented, said valve casing having portions opposite to said cylinder ports spaced from said valve to prevent seating of the valve in said portions, and one of said members having narrow closely spaced longitudinal serrations, the outer faces of which are in substantially seating contact with the other member at opposite sides of said cylinder port of about one half the width of the intervening grooves.

45 8. A rotary valve mechanism for multi-cylinder, internal combustion engines including a valve casing member having a plurality of axially spaced sets of peripherally spaced ports, a rotary valve member in said chamber and including a plurality of sections, one section for each set of ports and each section having a passage for interconnecting the ports of said set, a plurality of roller bearings in said casing for supporting and centering said valve member, each bearing being disposed between two adjacent valve sections for supporting both, whereby flexing of said valve member, by variation in the pressure exerted thereon through said cylinder port is prevented, said valve casing having portions opposite to said cylinder ports spaced from said valve to prevent seating of the valve in said portions, and one of said members having a series of narrow closely spaced longitudinally extending alternate grooves and ridges, the outer faces of the ridges having substantially gas-tight seating contact with the other member at opposite sides of said cylinder port, and said valve member having substantially annular fine grooves between each section and the adjacent bearing to retard flow of gas endwise of said casing.

RUDOLPH WEHR.
